UNITED STATES PATENT OFFICE.

CHRISTIAN P. SMITH, OF SOUTH BEND, INDIANA; ARTHUR L. JONES ADMINISTRATOR
OF SAID CHRISTIAN P. SMITH, DECEASED.

CUTTER-HEAD.

1,400,245.

Specification of Letters Patent. Patented Dec. 13, 1921.

Application filed November 5, 1919. Serial No. 335,969.

To all whom it may concern:

Be it known that I, CHRISTIAN P. SMITH, a citizen of the United States, residing at South Bend, in the county of St. Joseph and 5 State of Indiana, have invented certain new and useful Improvements in Cutter-Heads, of which the following is a specification.

The invention relates to a cutter head for wood working machinery, such as shapers 10 and planers, and has for its object the provision of means designed for more securely holding the cutting knives upon the supporting cutter heads. Another object resides in the provision of means for holding or clamp- 15 ing the knives to the cutter head in a manner which permits a greater portion of the knife blades, as they are worn away in the sharpening process, to be used and effectively held to place, thus prolonging the use- 20 fulness of the knives materially over the type of cutter heads and knife clamping means as now generally employed, whereby a considerable saving in the cost of replacements of the relatively expensive cutting 25 knives is effected. Still another object resides in the provision of a clamping means for holding the cutting knife to the cutter head, which will function to exert a tremendous pressure upon the cutting edge of the 30 knife, and thus prevent shavings and splinters from working in between the knife blade and the cutter head, and acting as a wedge with a tendency to force said members apart.

With the foregoing and other objects in 35 view, the invention in the preferred form of details will be described in the following specification, reference being had particularly to the accompanying drawings, in which:—

40 Figure 1 is an end elevation, partly in section, of a cutter head embodying the improvement.

Fig. 2 is a top or plan view thereof, with the cutter head in the position shown in 45 Fig. 1.

As appears in the drawings, the cutter head 3 is of the usual form, being provided with T-form slots 4 extending the full length thereof, and outwardly extending lip portions 50 5 at diagonal corners thereof, the type shown being adapted for the reception of two cutting knives. Inasmuch as the knives and the securing means therefor are identical, a showing of one and description thereof is 55 deemed sufficient for all practical purposes.

Adapted to be mounted upon the cutter head 3 is a knife blade 6, having a cutting edge 7, and preferably two or more slots 8 open toward the rear edge of the blade, whereby the blade may be adjusted in effective position, as the cutting edge thereof becomes worn away in the sharpening process, with respect to clamping bolts 9 which pass through said slots. Adapted to bear upon the knife blade is what may be termed a 60 clamping bar 10, apertured to permit the clamping bolts to pass therethrough, and which bar is of flexible metal, but flexible only under great stress. Threaded through the clamping bar at the end opposite the cutting edge of the knife blade, are screw members 11, preferably corresponding in number with the clamping bolts, and provided with slots 12 for the reception of a screw driver or other suitable tool for manipulating the same. The cutter head is provided with an aperture 13 for the reception of a spindle or shaft (not shown) for revolving the cutter head at a high rate of speed, as in 70 the manner and for the purpose well understood in the art.

As will be apparent from the drawings, the head ends of the bolts 9 are held in the slots 4 in a manner to anchor the same against movement radially of the axis of the cutter head, while at the same time adjustment thereof may be had lengthwise of the cutter head, which arrangement permits the ready removal of the bolts from the head for replacement or other purposes, and permits adjustment thereof so as to coincide with different spacings between the apertures or 80 slots in different knife blades.

The method of manipulating the improved knife clamping means is as follows: The 95 knife edge is first adjusted with respect to the edge of the cutter head, and the clamping bar applied thereon, with the screw members 11 in position to permit the clamping bar to be drawn as tight as possible upon the knife blade by manipulation of the clamping bolts, whereupon the screw members are turned to force the clamping bar end remote from the cutting edge of the knife away from the cutter head, which 100 action flexes the clamping bar and brings the end thereof bearing upon the knife blade under still greater stress. In such position of the clamping blade, and with the nuts 14 on the clamping bolts serving as a fulcrum, 105 110

great pressure will be exerted upon the knife blade adjoining its cutting edge, so that the cutting edge will at all times be held rigidly seated, and the displacement 5 thereof, as well as the yielding thereof sufficiently to prevent shavings and splinters from working in between the knife and the cutter head, effectively prevented. Obviously the clamping means may be manipulated in reverse order, that is—the end 10 of the clamping bar may first be raised away from the knife blade by the screw members 11, and the bolts 14 then drawn home, with the effect to flex the clamping bar in the 15 same manner and with the same results as first explained. In addition to the advantages already pointed out by the flexing of the clamping bar, the same exerts a constant and powerful tension against the underside 20 of the clamping nuts, thus serving as an effective nut lock, which, considering the high speed at which cutter heads are revolved and the danger which may result from any of the parts becoming loose or 25 placed, is of first importance.

While the foregoing is the preferred form of my invention, it is to be understood that I do not limit myself to the precise structure shown and described, as it is obvious 30 that same may be variously modified without departing from the spirit of the invention.

What is claimed is:—

1. The combination with a cutter head 35 having a flat knife blade receiving surface for the reception of a knife blade, of a flexible clamping bar having its under face flat and its rear edge extending beyond the rear edge of the knife blade and disposed 40 on said knife blade, a holding down bolt carried by the cutter head and spaced from its edges and passing through a notch in the knife blade and through an aperture in the flexible bar at a point spaced from its edges

and an adjusting screw threaded through 45 the flexible clamping bar adjacent its rear edge and rearwardly disposed in relation to the holding down bolt and forming means whereby the pressure of the flexible clamping 50 bar on the knife blade may be varied from a point adjacent the holding down bolt to its forward edge.

2. The combination with a cutter head 55 having a flat knife blade receiving surface for the reception of a knife blade, of a flexible clamping bar having its under face flat and its rear edge extending beyond the rear edge of the knife blade and disposed on said 60 knife blade, holding down bolts carried by the cutter head and spaced from its edges and passing through notches in the knife blade and through apertures in the flexible clamping bar at points spaced from each other and spaced from its edges, and adjusting 65 screws threaded through the flexible clamping bar adjacent its rear edge and rearwardly disposed in relation to the holding down bolts and forming means whereby the pressure of the flexible clamping bar on the knife may be varied from a point adjacent 70 the holding down bolts to its forward edge.

3. A knife blade securing device for cutter heads, said device comprising a holding down bolt carried by the cutter head and 75 spaced from its edge, the face of the cutter head being flat for the reception of a cutter blade, a clamping bar disposed on the cutter blade and provided with an aperture for the reception of the holding down bolt, a 80 nut threaded on the holding down bolt, means for flexing upwardly the rear side of the clamping bar for increasing the pressure on the cutter knife from a point adjacent the holding down bolt to its forward 85 edge.

In testimony whereof I affix my signature.

CHRISTIAN P. SMITH.
